UNITED STATES PATENT OFFICE.

JOHN M. MILLER, OF CRESTLINE, KANSAS.

HOLDER FOR DUST-PANS, BROOMS, AND DUST-BRUSHES.

SPECIFICATION forming part of Letters Patent No. 698,987, dated April 29, 1902.

Application filed February 19, 1902. Serial No. 94,757. (No model.)

To all whom it may concern:

Be it known that I, JOHN M. MILLER, a citizen of the United States, and a resident of Crestline, in the county of Cherokee and State 5 of Kansas, have invented a new and Improved Holder for Dust-Pans, Brooms, and Dust-Brushes, of which the following is a full, clear, and exact description.

This invention has for its object to provide 10 a novel simple device that is attachable upon the wall of a room at a suitable height from the floor and which affords convenient and reliable means for support of a dust-pan, broom, and dust-brush when the same are not 15 in use.

The invention consists in the novel construction and combination of parts, as is hereinafter described, and defined in the claims.

Reference is had to the accompanying 20 drawings, forming a part of this specification, in which similar characters of reference indicate corresponding parts in all the figures.

Figure 1 is a perspective view of the improvement secured upon a wall and in service 25 as a holder for a dust-pan, broom, and dust-brush. Fig. 2 is an enlarged detached front view of the improved holder. Fig. 3 is a transverse sectional view substantially on the line 3 3 in Fig. 2, and Fig. 4 is a longitudinal sectional view substantially on the line 4 4 in Fig. 2.

In the drawings, 5 indicates a back board whereon the holder proper is secured, and said board may with advantage be given an 35 oblong rectangular form and have perforations *a* at the corners to permit the insertion of screws or nails *a'* to secure the board upon an upright fixed support.

The holder is formed of a wire rod bent 40 into special form, as follows: At the longitudinal center of the wire rod a loop 6 is bent, thus providing two side members, which merge into two oppositely-turned coils 7, from which extend the remaining portions 8 of the wire rod, and on said portions members 9 are bent to extend in opposite directions in the same plane, as shown in Fig. 2. The alined portions 9 of the wire-rod material may be of equal length and at each 45 extremity have a hook 10 bent outward and upward.

The holder device formed of wire, as explained, is secured upon the back board 5 by staples 11, so that the spring-coils 7 will be free, and the hooks 10 project outward from 55 the back board near its ends and lower edge, as shown.

It will be seen that if the back board 5 is secured upon the side wall of a room at a suitable distance above the floor a dust-pan A 60 and dust-brush B may be readily hung upon respective hooks 10 and the handle of the broom C be clamped between the coils 7. Obviously the broom may be held with its head hanging near the floor, or said head may be 65 reversed in position, so as to be projected upwardly above the back board 5, the handle of the broom in either case being clasped between the spring-coils 7.

It will be apparent that the holder device 70 is very simple and efficient in service and affords convenient means for retention of the sweeping and dust-catching implements A, B, and C in place and at hand for removal from the holder as occasion may require. 75

While the back board 5 is shown as disposed horizontally, it may, if found desirable, be arranged vertically and the holder proper be correspondingly arranged upon the 80 back board.

It is practical to dispense with the back board 5 and secure the holder proper directly upon an upright wall or beam. Hence I do not limit my invention to the employment of the back board, but preferably employ it as an 85 adjunctive feature for the holder, that consists of the wire strand bent as hereinbefore described.

Having described my invention, I claim as new and desire to secure by Letters Patent— 90

1. A holder for dust-pans, brooms, dust-brushes or the like, comprising a wire rod bent to form two spaced spring-coils and depending members extended from said coils, portions of said members being bent in opposite 95 directions and having a hook formed on each free end.

2. A holder for dust-pans, brooms and dust-brushes, comprising a back board, and a holder device consisting of a single wire rod, 100 bent at the center into a loop having side members which merge into two oppositely-

turned spring-coils, depending members extended from the coils, alined horizontal members, bent oppositely, on the lower ends of the depending members, hooks turned outward and upward on the horizontal members at their free ends, and means for securing the holder device upon the back board.

In testimony whereof I have signed my name to this specification in the presence of two subscribing witnesses.

JOHN M. MILLER.
